DESIGN FOR A GAME BOARD

William J. Rogers, Maspeth, N. Y.

Application June 19, 1945, Serial No. 120,204

Term of patent 14 years

(Cl. D34—5)

To all whom it may concern:

Be it known that I, William J. Rogers, a citizen of the United States, residing at Maspeth, in the county of Queens, in the State of New York, have invented a new, original, and ornamental Design for a Game Board, of which the following is a specification, reference being had to the accompanying drawing, forming a part thereof.

Fig. 1 is a top perspective view of a game board, showing my design; Fig. 2 is a plan view, Fig. 3 is a side elevational view, and Fig. 4 is a bottom plan view, of the same.

I claim:

The ornamental design for a game board, as shown.

WILLIAM J. ROGERS.
